(57) **CLAIM**

The ornamental design for a lamp, as shown and described.

DESCRIPTION

FIG. 1 is a front, top, right-side perspective view of a lamp showing my new design, the bottom being plain, unornamented and not visible in use;

FIG. 2 is a rear, top, left-side perspective view thereof;

FIG. 3 is a front, top, right-side perspective view thereof with circular rib surrounding the central LED orifice and serving as a base for an illuminated object; and,

FIG. 4 is a front, top, right-side perspective view thereof with circular rib with the object shown in a dot-dash line.

1 Claim, 4 Drawing Sheets
